[57] **CLAIM**

The ornamental design for a scribe tool, as shown and described.

DESCRIPTION

FIG. 1 is a front perspective view of a scribe tool, in an open position, showing my new design;
FIG. 2 is a top plan view thereof;
FIG. 3 is a bottom plan view thereof;
FIG. 4 is a front elevational view thereof;
FIG. 5 is a rear elevational view thereof;
FIG. 6 is a top plan view thereof in closed position;
FIG. 7 is a left side elevational view of FIG. 6;
FIG. 8 is a right side elevational view of FIG. 6; and,
FIG. 9 is a sectional view thereof, to an enlarged scale,
the plane of the section being indicated by the line 9—9
in FIG. 6.
